Primary Examiner — T. Chase Nelson(74) *Attorney, Agent, or Firm* — Bryan Cave LLP(57) **CLAIM**

The ornamental design for a footwear sole, as shown and described.

DESCRIPTION

FIG. 1 is a perspective view of a footwear sole;
 FIG. 2 is a bottom perspective view thereof;
 FIG. 3 is another bottom perspective view thereof;
 FIG. 4 is a front view thereof;

FIG. 5 is a rear view thereof;
 FIG. 6 is a top view thereof;
 FIG. 7 is a right side view thereof; and,
 FIG. 8 is a left side view thereof.

The broken line showings in the figures are for the purpose of illustrating an environment only and form no part of the claimed design.

1 Claim, 8 Drawing Sheets# US D781,541 S
